UNITED STATES PATENT OFFICE.

ROBERT IRWIN HENDERSON, OF TORONTO, ONTARIO, CANADA.

CARBURETER.

1,393,367.

Specification of Letters Patent. Patented Oct. 11, 1921.

Application filed September 20, 1920. Serial No. 411,576.

To all whom it may concern:

Be it known that I, ROBERT IRWIN HENDERSON, a subject of the King of Great Britain, and resident of the city of Toronto, 5 county of York, Province of Ontario, in the Dominion of Canada, have invented certain new and useful Improvements in Carbureters, as described in the following specification and illustrated in the accompanying 10 drawings, that form part of the same.

The principal objects of the invention are to enable the accurate regulation of the flow of fuel in accordance with the change in the speed of the engine, to effect the thorough 15 carburation of the fuel and to provide a simple and effective structure which may be very accurately adjusted and will not be liable to get out of order.

A further object is to insure the maintenance of a supply of fuel in the carbureter 20 for starting the engine.

The principal feature of the invention consists in the novel construction and arrangement of parts whereby a valve controlling the flow of fuel to the carbureter is automatically regulated by the movement of the throttle and whereby said valve may be independently adjusted.

In the drawings, Figure 1 is a plan view 30 of my improved carbureter.

Fig. 2 is a horizontal longitudinal sectional view.

Fig. 3 is an enlarged sectional detail of the valve.

35 In the construction herein shown, the body 1 is of cylindrical form having a chamber 2 arranged upon the side wall and preferably formed integral therewith.

A fuel nozzle 3 is threaded into the side 40 wall of the body 1 from the inner side of the chamber 2, said fuel nozzle having a central opening 4 therethrough which is formed with a tapered portion 5 and the enlarged cylindrical portion 6 at the inner end.

45 The nozzle 3 projects into the cylindrical chamber 7 in the body 1 and a plurality of small holes 8 are bored through the side wall communicating with the tapered seat 5 of the orifice therein. These holes 8 are preferably arranged at an inward incline and are adapted to project fine streams of fuel 50 into the carbureter chamber.

A pin 9 extends across the cylindrical body portion of the carbureter, being arranged parallel to the axis of the opening

through the nozzle 3 and is located close to the said nozzle. A block 10 is slidably arranged on the pin 9 and is provided with a threaded hole 11 arranged in alinement with the axis of the nozzle. 60

A needle valve 12 formed with a threaded shank 13 is threaded into the block 10 and the reduced cylindrical portion 14 fits snugly into the cylindrical portion 6 of the nozzle and a tapered end 15 enters the tapered portion of the nozzle and is adapted to engage the valve seat 5.

The shank of the valve 12 extends outwardly through the side wall of the body 1 and is provided with a knurled head 16 70 by means of which it may be adjusted and a suitable spring arm 17 retains the adjustment by engagement with the knurled surface.

The block 10 is formed with a toothed 75 rack portion 18 on the opposite side of the pin 9 from the needle valve.

A pin 19 extends transversely of the body 1 in right-angular relation to the pin 9 and is arranged close thereto and upon this pin 80 is pivotally mounted a segment plate 20 provided with gear teeth 21 meshing with the rack 18 and at the other end with gear teeth 22 meshing with the gear 23 secured to the throttle 24. 85

As the throttle is opened or closed the gear 23 swings the plate 20 on its pivot, consequently sliding the block 10 upon the pin 9. This sliding movement is very limited owing to the gear ratio between the 90 teeth 22 and the teeth 21, but as the throttle is moved the needle valve carried by the block 10 is moved inwardly and outwardly in the nozzle 3. The needle valve may be adjusted by being turned in the threaded 95 block so that when the throttle is almost closed there will be a very slight flow of fuel through the opening 4 to the carbureter chamber 7 and as the throttle is opened the plate 20 is swung on its pivot and moves 100 the block 10, thereby moving the needle valve so as to create a larger opening in the tapered passage between the seat 5 and the valve 12, thus allowing a greater quantity of fuel to flow through the holes 8. The 105 motive fluid is thus regulated in exact relation to the set of the throttle.

The carbureter is provided with a choke 110 throttle 25 which operates in unison with the main throttle 24, being connected there-

with on the outer side of the body by the coil spring 26 secured between the arms 27 and 28 on the throttle spindles.

It will be noted that this choke throttle 5 directs the air inwardly against the wall of the carbureter through which the nozzle 3 extends, so that immediately upon the opening of the choke throttle a stream of air is projected directly against the said nozzle 10 to pick up and atomize the fuel.

A suitable filter screen 29 is arranged in the side chamber 2 and connected with this chamber is a check valve 30 which is adapted to retain the fuel contained within the 15 chamber 2 but will allow ready inflow to said chamber through the fuel supply pipe by the suction created by the engine.

It will be seen that as the throttle is opened, the needle is moved farther from its 20 seat and the suction within the carbureter chamber draws the fuel through the holes 8 and the fine streams of fuel thus projected are picked up by the current of air flowing through the carbureter.

25 A suitable plug 31 is arranged in the outer side of the chamber 2 so that the nozzle may be removed for cleansing purposes and it will be seen that with the construction of nozzle as herein shown, there will be practically no possibility of its becoming clogged in any way.

A carbureter such as described is extremely simple, there are no delicate parts to get out of order and everything is positively operated and it may be adjusted very accurately.

What I claim as my invention is:—

1. In a carbureter having a fuel nozzle entering the air passage and a throttle, a guide arranged diametrically in the air passage adjacent to the nozzle, a valve slidably supported on said guide and adapted to control the flow of fuel from the nozzle, and means arranged within the air passage and

directly engaging the throttle and said valve to slide said valve on said guide in relation 45 to the movement of the throttle.

2. In a carbureter having a fuel nozzle entering the air passage and a throttle, a guide arranged diametrically in the air passage adjacent to and parallel with the axis of the 50 nozzle, a block slidably arranged on said guide, a needle valve adjustably arranged in said block and carried thereby and adapted to control the flow of fuel from said nozzle, and means arranged within the air passage 55 and directly connecting said block with the throttle.

3. In a carbureter having a fuel nozzle entering the air passage and a throttle, a guide arranged diametrically in the air passage 60 adjacent to and parallel with the axis of the nozzle, a block slidably arranged on said guide, a pin extending diametrically across the air passage in right angular relation to said guide, and a lever member pivoted on 65 said pin and having one end engaging the slidable block and the other end connected with the throttle.

4. In a carbureter having a fuel nozzle entering the air passage and a throttle, a guide 70 arranged diametrically in the air passage adjacent to and parallel with the axis of the nozzle, a block slidably arranged on said guide and having rack teeth, a valve carried by said block and adapted to control 75 the flow of fuel from the nozzle, a pin extending diametrically across said air passage in right angular relation to said guide, a lever pivoted on said pin having a toothed end engaging the rack teeth of said block 80 and a toothed end engaging the rack teeth of said block and a toothed quadrant on the opposite end, and a gear quadrant on the throttle meshing with the toothed lever.

ROBERT IRWIN HENDERSON.
